SPOOL CARRIER

Rudolf Hirschfeld, New York, N. Y.

Application January 28, 1938, Serial No. 187,433

7 Claims. (Cl. 242—139)

My present invention relates generally to machines employing thread, such as sewing machines, and has particular reference to an improved spool carrier.

In commercial practice, an operator of a machine such as a sewing machine is called upon to utilize threads of differing types, varying, for example, in color or quality. It is, therefore, desirable that the operator have available for use a plurality of thread carriers, such as spools, for selective employment from time to time of one or another of the available threads. It is a general object of the present invention to provide an improved spool carrier for accomplishing this purpose.

The threads and yarns that are used by an operator are frequently of considerable intrinsic value and, therefore, it proves desirable in many cases to maintain an accurate check upon the amount of thread used.

It is a more specific object of the present invention to provide a spool carrier which prevents unauthorized removal of spools. Another object of the invention is to provide a device in which the spools are locked against unauthorized removal, but in which the spools are, nevertheless, mounted in readily accessible positions, permitting free withdrawal of thread without any likelihood of snarling.

A particular feature of my invention lies in an arrangement whereby the spools are so mounted that the thread may be withdrawn longitudinally. As a result, while the spools are mounted in freely rotatable manner, the withdrawal of thread does not induce unnecessary and undesirable rotation of the spools.

In a preferred embodiment, the spools are arranged with their axes substantially vertical, means being provided for withdrawing the thread in a substantially upward direction.

Briefly, my invention resides in the provision of a supporting panel with a spool rotatably mounted on its obverse side; the provision of an abutment spaced from the panel and aligned with the spool for preventing withdrawal of the spool from the panel; and the provision of enclosable means on the reverse side of the panel for securing the abutment against movement away from the panel. Preferably, the spool is mounted upon a pin which extends through the panel, the abutment being arranged on the pin, itself, and the rear end of the pin being releasably engaged by a nut which may be enclosed to bar unauthorized access to it.

I achieve the foregoing objects, and such other

objects as may hereinafter appear or be pointed out, in the manner illustratively exemplified in the accompanying drawing, wherein—

Figure 1 is a plan view of a spool carrier constructed in accordance with the present invention, the thread being omitted; and

Figure 2 is an enlarged cross-sectional view taken substantially along the line 2—2 of Figure 1, with the spools in position.

I have illustratively shown the invention applied to a spool carrier intended primarily for use with sewing machines, but it will be understood that certain phases of the invention have a far wider applicability. Also, in the illustrated embodiment, I show a spool carrier adapted to accommodate twenty spools but, obviously, the invention may be utilized with only one spool or with as large a plurality of spools as may be desirable.

In accordance with my invention, a panel 10 is provided with a series of suitably spaced openings within which pins 11 are mounted. Each pin has an attenuated end portion, preferably exteriorly threaded, which extends through the panel 10 so that it may be releasably engaged by a thumb nut 12 or the like on the reverse side of the panel 10.

At its outer end, each pin is provided with the enlargement or abutment 13.

Each pin is of such a size that it may conveniently accommodate a spool 14 which loosely encircles the pin. I have illustratively shown spools of the character in which the lower end is in the form of a relatively wide flange 15, while the opposite end is devoid of such a flange. The thread 16, wound upon the spool, is adapted to be used by guiding it upwardly over any selected guide hook 17, and thence to the sewing machine or other apparatus where the thread is to be used.

The panel 10 is constructed in the form of a lid or cover for a box-like enclosure which I have illustratively shown with a bottom wall 18 and upstanding side walls 19. The lid or panel 10 is removably associated with this box-like enclosure, and I have illustratively shown a hinge 20 at one side of the device and a loop-and-hasp arrangement 21 at the opposite side of the device. A padlock 22, or similar locking means, serves to lock the panel 10 to the enclosure.

In use, a suitably authorized person removes the lock 22 and elevates the panel 10 so as to make its reverse side accessible. Any desired one or more of the thumb nuts 12 is then released, whereupon the corresponding pin 11 may be withdrawn outwardly. The desired spool of

thread is then slid over the pin 11, and the latter is replaced into association with the panel 10, the thumb nut 12 being then reapplied. This firmly secures the pin 11 to the panel 10 and secures the abutment 13 against movement away from the panel. Nevertheless, the spool is loosely mounted on the pin so that it may freely rotate, if necessary; and the spool is readily accessible for withdrawing thread from it in a substantially longitudinal direction. After all the desired spools of thread are mounted in association with the panel 10, the latter is then secured to the enclosure beneath it; and the lock 22 or other locking means is then reapplied so as to bar unauthorized access to the nuts 12.

As a result of this arrangement, an operator in need of additional thread must necessarily apply to an authorized party to manipulate the present spool carrier in order to gain access to the reverse side of the panel and thereby permit removal of an empty spool and replacement by another. In this way, an accurate check may be retained over the amount of thread that is used.

In the illustrated embodiment, the panel 10 has been shown octagonal in shape, and the box-like enclosure beneath it is of corresponding shape. It will be understood, however, that the device need not necessarily embody this particular configuration. It will also be understood that the device may rest loosely on a machine or pedestal; or the bottom wall 18 may be rigidly secured either upon a supporting pedestal or in any other desired manner.

The enclosure beneath the panel and the panel, itself, may be conveniently made of wood or any other suitable material. The pins 11 are preferably metallic. The guide hooks 17 may be formed at the extremities of radiating arms secured in adjustable manner upon a central post 23 mounted on the panel 10.

I draw particular attention to the fact that the present arrangement leaves the spools in readily accessible position, so that the withdrawal of thread is a relatively simple matter which does not interfere with nor impair the smooth continuity of the work which the operator is engaged in. Furthermore, the withdrawal of the thread in a freely upward direction usually involves little or no rotation of the individual spools, and in this way there is little likelihood of any excessive pull upon the spools which might engender the snarling of excess thread.

In general, it will be understood that changes in the details, herein described and illustrated for the purpose of explaining the nature of my invention, may be made by those skilled in the art without departing from the spirit and scope of the invention as expressed in the appended claims. It is, therefore, intended that these de-

tails be interpreted as illustrative and not in a limiting sense.

Having thus described my invention and illustrated its use, what I claim as new and desire to secure by Letters Patent is—

1. In a spool carrier, a supporting panel, a spool rotatably mounted on the obverse side of the panel, an abutment spaced from the panel and aligned with the spool for preventing withdrawal of the spool from the panel, releasable means on the reverse side of the panel for securing said abutment against movement away from the panel, and a removable box-like enclosure for said releasable means, said enclosure having means for locking the same to prevent unauthorized access to the interior thereof. 15

2. In a spool carrier, the elements set forth in claim 1, said enclosure comprising a box-like member separably associated with said panel on the reverse side of the latter. 20

3. In a spool carrier, the elements set forth in claim 1, said enclosure comprising a box-like member hinged to said panel to permit relative pivotal movement of the enclosure and panel. 25

4. In a spool carrier, the elements set forth in claim 1, said enclosure comprising a box-like member having a bottom wall serving as a support for the spool carrier, and upstanding side walls, the panel conforming in shape to that of said bottom wall so as to serve as a cover for 30 the box-like member.

5. In a spool carrier, a supporting panel, a pin extending through said panel, a spool rotatably mounted on said pin on the obverse side of the panel, an abutment on the pin for preventing 35 outward withdrawal of the spool from the pin, releasable means on the reverse side of the panel for engaging the pin to secure it against outward withdrawal from the panel, and a removable box-like enclosure for said releasable means, said enclosure having means for locking the same to prevent unauthorized access to the interior thereof. 40

6. In a spool carrier, the elements set forth in claim 5, said pin having a threaded end, and said 45 releasable means comprising a nut engageable with said threaded end.

7. A spool carrier comprising a box-like enclosure having means for locking the same to prevent unauthorized access thereto, a spool supporting pin at the obverse side of said enclosure and having an end portion removably projecting through a wall thereof, the opposite end portion of said pin having an abutment for preventing outward withdrawal of a spool from said pin, and releasable means within the enclosure for engaging the inner end portion of the pin to secure it against outward withdrawal from the enclosure. 55
